UNITED STATES PATENT OFFICE.

EDWIN N. PREBLE, OF BEVERLY, MASSACHUSETTS, ASSIGNOR TO UNITED SHOE MACHINERY COMPANY, OF PATERSON, NEW JERSEY, A CORPORATION OF NEW JERSEY.

STARTING AND STOPPING MECHANISM.

1,174,346.

Specification of Letters Patent.

Patented Mar. 7, 1916.

Application filed December 30, 1910. Serial No. 600,145.

To all whom it may concern:

Be it known that I, EDWIN N. PREBLE, a citizen of the United States, residing at Beverly, in the county of Essex and State 5 of Massachusetts, have invented certain new and useful Improvements in Starting and Stopping Mechanism; and I do hereby declare the following to be a full, clear, and exact description of the invention, such as 10 will enable others skilled in the art to which it appertains to make and use the same.

The invention relates to mechanism for controlling the starting and stopping of the driving shaft, or other rotary element, 15 through which the operating parts of the machine are driven and more especially to mechanism which is adapted for use in controlling the operation of machines such, for instance, as sole molding, direct pressure 20 sole leveling, or sole laying machines in which the driving mechanism is manually thrown into operation through a treadle or a similar device.

In existing mechanism of this general 25 type it is customary to automatically stop the operation of the machine at a predetermined point by throwing out the driving clutch and simultaneously applying a brake which operates to stop the machine instantaneously. The brake is applied by a movement of the shipper rod which disengages the driving clutch and it is found that in some instances the clutch sticks sufficiently to prevent the movement of the shipper rod 30 and as the brake is not applied the machine continues to operate. When this happens the machine is said to repeat, which is especially objectionable in sole molding or sole laying machines where it is desired to stop 35 the machine with one lower form in a position of presentation convenient to the operator, and with the other lower form in operative engagement with the upper form.

The object of the present invention is to 40 provide an improved starting and stopping mechanism which is under the control of the operator to start the machine and which operates automatically to stop the machine at a predetermined point in the cycle of operations without liability of the machine 45 repeating.

With this object in view, one feature of the invention consists in the combination,

with a clutch and brake and means for disengaging the clutch, of actuating mechanism for the brake operated independently of the means for disengaging the clutch to apply the brake at a certain predetermined point in the cycle of operations.

Still further features of the invention 55 consists in certain novel features of construction, combinations and arrangements of parts hereinafter described and claimed, the advantages of which will be obvious to those skilled in the art from the following 60 description.

In the accompanying drawings illustrating the preferred form of the invention Figure 1 is a side elevation of a machine embodying the various features of the invention in their preferred form, Fig. 2 is a plan view of the devices for automatically disengaging the clutch and applying the brake, Fig. 3 is a sectional side elevation of the device shown in Fig. 2 and illustrating the device in its operative position. Fig. 4 is a sectional plan view, upon an enlarged scale, of a portion of the device employed for operating the brake, and Fig. 5 is a sectional side elevation of the portion of the 70 device shown in Fig. 4, showing the device in its inoperative position with the brake applied.

In the drawings the various features of the invention are shown embodied in a well known type of machine for operating upon shoe soles in which two sets of forms for subjecting the soles to pressure are alternately actuated through two cranks and connecting toggles. It will be understood, 80 however, that the invention is not limited in its application to such a machine but may be used in various other types of machines.

In the machine shown in the drawings, 85 the crank shaft is indicated at 1 and is provided with two cranks 2 and 3 arranged at an angle of 180° to each other, as is usual in this type of machines. The cranks are respectively connected, through the links 5 and 6 and toggles 8 and 9, to the movable lower forms 10 and 11 which coöperate with stationary upper forms fixed in the upper portion of the machine frame 12. For the sake of clearness, and as this construction forms no part of the present in- 90 95 100 105

vention, these parts have only been shown in dotted outline in Fig. 1.

The crank shaft is driven from a driving shaft 15 through a train of gears comprising the gear 16 mounted upon the driving shaft, the intermediate gears 17 and 18 and the large gear 19 mounted upon the crank shaft, as is usual in this type of machine. The shaft 15 is driven through a pulley 20 which is mounted to revolve freely on the shaft and move longitudinally thereon. The pulley is provided with a friction surface forming one member of a clutch, the other member 21 of which is connected to 15 rotate with the shaft 15. The pulley 20 is shifted to engage and disengage the clutch through a bell crank 23, one end of which is connected with the pulley 20 by means of studs 24 which engage an annular groove 25 formed in the hub of the pulley. The other end of the clutch lever 23 is pivotally connected to a block 26 which is adjustably secured upon the end of a shipper rod 27, the block being held in adjusted position 25 by means of the set screw 28. The front end of the rod 27 is provided with a flanged sleeve 29 detachably mounted thereon and the flanged portion of the sleeve engages with a recess formed in the treadle lever 30 in order to operatively connect the shipper rod and treadle lever. The treadle lever is pivoted at 31 to the frame of the machine and is provided at its front end with a boss 32 in which the treadle 33 is adjustably 35 mounted.

Under normal conditions it is desirable to provide means for locking the clutch in its operative position until a predetermined point is reached in the cycle of operations 40 of the machine. The locking means are then automatically disengaged and the shipper rod is moved to return the clutch to its normal inoperative position. To this end the machine is provided with what may be 45 termed a tripping lever 34 which is pivotally mounted on the main driving shaft of the machine and is provided at its upper end with a pair of rolls 35 and 36 arranged to be engaged by the cranks 2 and 3, respectively. The rolls are journaled in the upper ends of forked arms 38 and 39 which are pivotally mounted upon a transverse shaft 40 journaled in the upper end of the tripping lever 34. The rolls are held in 55 any adjusted position by a pair of screws 41 and 42 which are mounted in the upper end of the lever 34 and respectively bear against the rear faces of the arms 38 and 39. A sleeve 45 is connected to move longitudinally with the shipper rod 27 and is provided with a bearing surface 46 upon its upper face. The tripping lever 34 is formed as a bell crank lever pivoted upon the driving shaft 15 and the lower free end of the 60 lever is arranged to drop behind the front 65

face of the sleeve 45 and retain the sleeve and shipper rod in a fixed position upon a sufficient movement of the shipper rod 27 to engage the clutch. In order to provide a better operative connection between the 70 parts, the tripping lever is provided with a cam roll 47 which normally rides on the bearing surface 46 but is arranged to drop down behind the front face of the sleeve upon a sufficient movement of the sleeve in 75 a longitudinal direction. The shipper rod is held in this position while the crank shaft makes a half revolution and when the cranks reach the relative positions shown in Fig. 1, the tripping lever 34 is positively 80 oscillated by the crank 2 a sufficient amount to disengage the roll 47 from the front face of the sleeve 45. The sleeve and shipper rod are then returned to their normal positions to disengage the clutch by a tension 85 spring 54 which operatively connects the sleeve and the upper arm of the tripping lever 34.

Under some conditions it is desirable to place the starting and stopping of the machine directly under the control of the operator and for this purpose an improved mechanism has been devised for locking the sleeve 45 to the shipper rod in different 90 relative longitudinal position without varying the extent of movement or the initial position of the treadle. When the starting and stopping of the machine is to be directly under the control of the operator, the sleeve is moved back upon the shipper 95 rod and locked in this position so that upon the longitudinal movement of the shipper rod and sleeve to engage the clutch, the cam roll 47 will not ride off the end of the sleeve and lock the shipper rod in position. To 100 this end the sleeve 45 is slidably mounted upon the shipper rod and is connected thereto by a rod 48. The rod 48 is connected at one end to a projecting lug 49 formed upon the sleeve and at its opposite end passes 105 loosely through a slot formed in the upper portion of the treadle lever 30. The rod 48 is conveniently held in the proper relation to the treadle lever by a pin and slot connection shown clearly in Figs. 1 and 3. 110 The outer end of the rod 48 is provided with a latch dog 50 pivotally connected thereto. The latch dog 50 has a nose 51 which normally engages with a head 52 mounted upon the end of the shipper rod 27. In this position the sleeve 45 is in its advanced position and upon a longitudinal movement of the shipper rod the roll 47 will ride off the end of the sleeve and the stopping of the 115 machine is automatically controlled thereby. When it is desired to place the stopping of the machine under the control of the operator, the latch dog 50 is turned through an angle of 90° into a position in which the face 53 engages with the treadle 120 125 130

lever 30. The rod 48 is then immediately moved back to bring the dog into this position by the spring 54 connected to one end thereof. This moves the sleeve 45 back a sufficient distance to prevent the bearing surface 46 of the sleeve moving out of engagement with the roll 47 when the shipper rod is actuated to engage the clutch and in this case the stopping of the machine is directly under the control of the operator and the clutch will be immediately disengaged by the spring 54 upon releasing the treadle 32.

Upon depressing the treadle, it is essential that the brake shall be released before or at the same time that the clutch is engaged to start the machine. Upon stopping the machine it is desirable that the brake shall be applied independently of the means for disengaging the clutch in order that the movement of the machine shall be immediately stopped even though the clutch is not wholly disengaged. The automatic stopping devices are accordingly constructed and arranged so that the brake is positively applied at the proper time by mechanism operating independently of the clutch operating devices. In the preferred form of the invention the tripping lever is utilized to actuate the brake in addition to locking the clutch in operative position. When the machine is stopped the tripping lever is retained by the cranks in the position shown in Fig. 1 and in this position the tripping lever is arranged to apply the brake. It is therefore necessary to provide auxiliary means for releasing the brake prior to the starting of the machine as the tripping lever is held in this position until after the machine has started and the crank shaft has rotated a portion of a turn. The auxiliary means are arranged to release the brake immediately upon the movement of the shipper rod to engage the clutch so that the brake is released before or at the same time that the clutch is engaged to start the machine. To this end the tripping lever is provided upon its lower end with a U-shaped frame 56 in which is supported a toggle lever comprising two arms 57 and 58. The lower end of the arm 57 is pivotally connected at 59 to the U-shaped frame 56 and the upper end of the arm 58 is pivotally connected to a bearing plate 60. The plate 60 is connected at one end to a projecting lug 61 formed upon the upper portion of the frame 56. The upper face of the plate 60 forms a bearing surface for the lower end of a screw 62 which is mounted in the outer end of a brake operating arm 63 so that upon a movement of the plate 60 the operating arm 63 is moved correspondingly in order to actuate the brake. The brake operating arm and connections between the arm and tripping lever may be

conveniently referred to as a brake actuating mechanism. In order to release the brake preliminarily to the starting of the machine, means is provided for securing a downward movement of the bearing plate 60 relatively to the tripping lever 34. For this purpose means is provided for breaking the toggle upon a longitudinal movement of the shipper rod due to the depression of the treadle. The central point of the toggle is pivotally connected to an operating rod 64 which is provided with a notch upon its under face normally engaging with a projecting pin 65. A sleeve 66 is clamped upon the shipper rod and is provided with a slotted portion in which the pin 65 is fastened. The rod 64 passes through the slot and the notch in the under face of the rod engages with the pin 65. Thus upon depressing the treadle the operating rod 64 is moved longitudinally and the toggle is broken. This allows the plate 60 and consequently the arm 63 to drop down and release the brake as will be hereinafter described.

It will be apparent from an inspection of Fig. 5 that the operating arm 63 is sufficiently heavy to move downwardly under the action of gravity and release the brake when allowed to do so upon a movement of the plate 60. Upon a still further movement of the shipper rod 27, the cam roll 47 rides off the bearing surface 46 and as soon as the crank shaft has rotated sufficiently to permit a movement of the tripping lever 34, the end of the lever carrying the frame 56 drops down behind the sleeve 45. This, of course, permits a still further movement of the operating arm 63 but this movement, is not sufficient to affect the operation of the brake. In order to return the operating mechanism for the brake into a position in which the brake will be applied upon an upward movement of the tripping lever to release the shipper rod, means are provided for breaking the operative connection between the toggle and shipper rod and for straightening the toggle. With this in view, a pin 67 is positioned below the middle of the rod 64 and upon a downward movement of one end the rod fulcrums about this pin and the pin 65 is disengaged from the recess in which it is seated. The rod is then moved back to its initial position, by a tension spring 68 which connects the rod and U-shaped frame 56, as shown clearly in Fig. 4. The operating rod 64 is normally retained in operative engagement with the shipper rod 27 by a tension spring 69 which connects the rod with a projecting arm 70 formed integrally with the sleeve 66. Upon a movement of the tripping lever, in order to release the clutch, the operating arm 63 is moved upwardly to simultaneously apply the brake and it can readily be seen that this

application of the brake is positive and does not depend for its action upon the return movement of the shipper rod 27.

It is desirable to employ a brake which 5 may be applied with considerable force to immediately overcome the inertia of the moving parts and it is furthermore desirable that the application of the brake shall be accomplished with a relatively slight 10 movement of the operating mechanism and shall only require a comparatively small force to obtain this movement. The improved brake which is employed for this purpose comprises an annular ring 71 which 15 is mounted upon the main driving shaft and a pair of curved brake shoes 72 and 73 which operatively engage with the inner face of the annular ring to retard its rotation. The brake shoes are pivoted at 74 at one end to 20 a transverse arm 75 which is loosely sleeved upon the shaft 15. The opposite free ends of the brake shoes are moved apart in order to apply the brake by a cam projection 76 which projects between the free ends of the 25 brake shoes 72 and 73. When the cam projection rests in the position shown in Fig. 3, the brake shoes are allowed to come together and release the brake and when the cam projection is partially turned, as shown in Figs. 30 1 and 5, the free ends of the brake shoes are forced apart to positively apply the brake. In order to lift the brake shoe 73 out of engagement with the annular ring 71 when the 35 brake is released, a tension spring 77 is inserted between the arm 75 and the brake shoe. The cam projection 76 is mounted upon the curved operating arm 63 and is provided with an intermediate cylindrical portion which is journaled in one end of the 40 arm 75.

While it is preferred to employ the specific construction and arrangement of parts shown and described, it will be understood that this construction and arrangement is 45 not essential except so far as specified in the claims, and may be changed and modified without departing from the broader features of the invention.

I claim:

50 1. A starting and stopping mechanism, having, in combination, a clutch, a friction brake, means under the control of the operator arranged to simultaneously release the brake and engage the clutch, and mechanism 55 arranged to positively apply the brake at a predetermined point, substantially as described.

60 2. A starting and stopping mechanism, comprising a clutch, a brake, means arranged to release the brake and engage the clutch, means for disengaging the clutch, and means for applying the brake operating independently of the means for disengaging the clutch, substantially as described.

65 3. A starting and stopping mechanism,

comprising a clutch, a brake, a shipper rod arranged to operate the clutch, connections between the shipper rod and brake arranged to release the brake upon a movement of the shipper rod to engage the clutch, means for 70 disengaging the clutch, and means for applying the brake operating independently of the means for disengaging the clutch, substantially as described.

4. A starting and stopping mechanism, 75 having, in combination, a clutch, means normally tending to retain the clutch in an inoperative position, a brake, means under the control of the operator arranged to simultaneously release the brake and engage the clutch, locking means arranged to retain the clutch in operative position, and mechanism arranged to positively apply the brake and release the locking means at a predetermined point, substantially as described.

85 5. A starting and stopping mechanism, having, in combination, a clutch, means normally tending to retain the clutch in an inoperative position, a brake, means under the control of the operator arranged to simultaneously release the brake and engage the clutch, locking means arranged to retain the clutch in operative position, a tripping lever, operative connections between the tripping lever and the brake, and mechanism for 90 positively actuating the tripping lever to apply the brake upon a movement to release the locking means, substantially as described.

95 6. A starting and stopping mechanism, having, in combination, a clutch, a shipper rod positively connected to the clutch, means operatively engaging with the shipper rod and normally tending to retain the clutch in an inoperative position, a brake, a tripping lever operatively connected to the 100 brake, means under the control of the operator arranged to move the shipper rod and engage the clutch, locking means arranged to retain the clutch in operative position, and a crank arranged to engage with the 105 tripping lever at a predetermined point and move the tripping lever to positively apply the brake and release the locking means, substantially as described.

110 7. A starting and stopping mechanism having, in combination, a clutch, a shipper rod for disengaging the clutch, a brake, a tripping lever, connections between the tripping lever and brake, and means for actuating the tripping lever to positively apply the 115 brake at a predetermined point in the cycle of operations, substantially as described.

120 8. A starting and stopping mechanism having, in combination, a clutch, a shipper rod for engaging the clutch, a brake, a tripping lever, connections between the tripping lever and brake, and connections between the tripping lever and shipper rod for releasing the brake upon a longitudinal 125 movement of the shipper rod prior to en- 130

gaging the clutch, substantially as described.

9. A starting and stopping mechanism comprising a brake, a bell crank lever supported adjacent thereto, an operating arm, operative connections between the arm and bell crank for positively actuating the arm upon a movement of the bell crank and mechanism for automatically imparting an oscillatory movement to the bell crank to actuate the brake, substantially as described.

10. A starting and stopping mechanism, having in combination, a clutch, a shipper rod for the clutch, a brake, a tripping lever for positively applying the brake at a predetermined point in the cycle of operations, mechanism for actuating the tripping lever, and means arranged to release the brake upon movement of the shipper rod to engage the clutch, substantially as described.

11. A starting and stopping mechanism, having, in combination, a clutch, a shipper rod, a brake, a tripping lever arranged to apply the brake, and means supported upon one end of the tripping lever and arranged to release the brake upon a movement of the shipper rod to engage the clutch, substantially as described.

12. A starting and stopping mechanism having, in combination, a clutch, a brake, a shipper rod for engaging the clutch, a tripping lever arranged to apply the brake, actuating mechanism for the brake connected to the tripping lever, and means arranged to release the brake through the actuating mechanism upon movement of the shipper rod.

13. A starting and stopping mechanism having, in combination, a clutch, a shipper rod, a tripping lever, a toggle supported at one end of the tripping lever, a brake, operative connections between the toggle and brake, and connections between the shipper rod and toggle arranged to break the toggle and release the brake upon a longitudinal movement of the shipper rod to engage the clutch, substantially as described.

14. A starting and stopping mechanism, having, in combination, a clutch, a shipper rod, a tripping lever, a toggle supported at one end of the tripping lever, a brake, operative connections between the toggle and brake, and connections between the shipper rod and toggle arranged to break the toggle and release the brake upon a longitudinal movement of the shipper rod to engage the clutch, means arranged to break the operative connections between the toggle and shipper rod at a predetermined point in the movement of the shipper rod, and a spring

arranged to straighten the toggle when the connections are broken, substantially as described.

15. A starting and stopping mechanism comprising a clutch, a shipper rod connected thereto, a treadle lever connected to the shipper rod, a sleeve supported upon the rod, and means for determining the position of the sleeve relative to the rod comprising an operating rod connected to the sleeve and a latch dog pivotally mounted upon the free end of the operating rod and arranged to engage with the end of the shipper rod to hold the sleeve in a predetermined position with relation to the shipper rod, substantially as described.

16. A starting and stopping mechanism having, in combination, a brake, a tripping lever, a toggle supported upon one end of the tripping lever, operative connections between the toggle and brake, a clutch, a longitudinally movable shipper rod for the clutch, a rod connected to the central point of the toggle and having a recess formed in its under face, a pin mounted to move with the shipper rod and arranged to normally engage with the recess, a stud projecting beneath the central portion of the rod, and means upon the shipper rod arranged to allow one end of the tripping lever and the toggle to move bodily downward upon a sufficient movement of the shipper rod to engage the clutch, the rod connecting the toggle being arranged to fulcrum about the stud upon the bodily downward movement of the toggle and disengage the pin from the recess, and a spring arranged to straighten the toggle, substantially as described.

17. A starting and stopping mechanism, having in combination, a brake, a clutch, a shipper rod for actuating the clutch, means for normally moving the shipper rod to engage the clutch, and means for positively applying the brake acting automatically when the clutch is disengaged, substantially as described.

18. A starting and stopping mechanism, having in combination, a clutch, a brake, a shipper rod, a tripping lever arranged to lock the shipper rod with the clutch held in an operative position, connections between the tripping lever and brake, and means for actuating the tripping lever to release the shipper rod and apply the brake at predetermined intervals, substantially as described.
